UNITED STATES PATENT OFFICE.

WILLIAM B. STOUGHTON, OF DUBOIS, PENNSYLVANIA, ASSIGNOR TO STOUGHTON HARP COMPANY, OF DUBOIS, PENNSYLVANIA, A CORPORATION OF DELAWARE.

DESIGN FOR A HARP.

Application filed June 19, 1923. Serial No. 6,531. Term of patent 7 years.

To all whom it may concern:

Be it known that I, WILLIAM B. STOUGHTON, a citizen of the United States of America, residing at Dubois, in the county of Clearfield and State of Pennsylvania, have invented a new, original, and ornamental Design for a Harp, of which the following is a specification, reference being had to the accompanying drawing, forming a part hereof.

In the drawing:

Figure 1 is a side elevation of a harp showing my design, and

Fig. 2 is a rear elevation of the same.

I claim:

The ornamental design for a harp, as shown.

WILLIAM B. STOUGHTON. [L. S.]
